(No Model.)

E. E. ANGELL.
ELEVATOR LOCK.

No. 411,274.

Patented Sept. 17, 1889.

UNITED STATES PATENT OFFICE.

EDWIN E. ANGELL, OF BOSTON, MASSACHUSETTS.

ELEVATOR-LOCK.

SPECIFICATION forming part of Letters Patent No. 411,274, dated September 17, 1889.

Application filed January 14, 1889. Serial No. 296,246. (No model.)

To all whom it may concern:

Be it known that I, EDWIN E. ANGELL, of Boston, in the county of Suffolk and State of Massachusetts, have invented certain new and useful Improvements in Elevator-Locks, of which the following is a specification.

This invention has for its object to provide a simple, effective, and easily-operated attachment whereby a merchandise-elevator may be locked to and released from a collar on the rope which stops and starts the operating mechanism; and to this end the invention consists in the improved locking devices which I will now proceed to describe and claim.

Of the accompanying drawings, Figure 1 represents a perspective view of an elevator having my improved lock. Fig. 2 represents a side view of the lock, its supporting-standard, and a portion of the starting and stopping rope. Fig. 3 represents a section on line *x* *x*, Fig. 2. Fig. 4 represents a section on line *y* *y*, Fig. 3. Fig. 5 represents a section on line *z* *z*, Fig. 2.

The same letters of reference represent the same parts and features in the different drawings.

In the drawings, *a* represents the platform of an elevator or lift, and *b* represents the usual shipping-rope, which has collars *c* *c'*, located at different points, adapted to be grasped by locking devices supported by the platform, the engagement of either of said collars by the locking devices while the platform is in motion giving the rope a movement which stops the operating mechanism and arrests the motion of the platform in a manner which is well understood and needs no particular description.

My improved locking devices comprise two jaws *c* *c'*, which are pivoted at *d* to a holder or casing *e*, said holder being attached to a vertical standard *f*, which is attached at its lower end to the platform *a*. The swinging ends of the jaws are curved, as shown in Fig. 3, and are formed so that when they are closed, as shown in full lines, the space between their inner sides will be less than the diameter of the collars on the rope; but when they are opened, as shown in dotted lines, said space will be greater than the diameter of said collars. The jaws are normally held

in their closed position by springs *g* *g*, attached to their outer sides and bearing against the inner sides of the holder *e*, said springs yielding and permitting the jaws to be opened. 55

h represents a lever or key which is pivoted at *i* below the jaws to the holder *e* and projects upwardly through an opening *i* between the jaws, said opening being formed by recessing the inner sides of the jaws. The 60 said opening is wider than the thickness of the lever, so that when the lever is thrown forward, as shown in Fig. 3 and in full lines in Figs. 2 and 4, it permits the jaws to be closed by the springs *g* *g*; but when the lever is thrown back, as shown in dotted lines in Figs. 2 and 4, it comes between the cheeks or sides 2 2, which form a narrower opening 65 communicating with the opening *j*, and by contact with said sides forces the jaws apart 70 to the position shown in dotted lines in Fig. 3. It will be seen, therefore, that when the jaws are held apart by the key or lever *h* they are entirely inoperative, because the collars will pass between their outer ends without 75 engagement therewith. Each collar has a tapered end 4 and a square or flat end 3, as usual. When the jaws are closed, they are adapted to engage any collar which is arranged with its square or flat end 3 toward 80 the advancing jaws, the closed ends of the jaws coming to a bearing on said square or flat end, as shown in Fig. 4, and giving the rope the movement required to stop the operating mechanism. The collars are arranged 85 in pairs, the collar *c'* of each pair having its square end at the top and engaging the jaws during the descent of the elevator, while the other collar *c* has its square end at the bottom and engages the jaws during the ascent 90 of the elevator, the jaws yielding when they encounter the tapered end of any collar which presents said tapered end to the advancing jaws and closing after passing over said collar. 95

The holder *e* is provided with two trumpet-shaped tubes or guides *k* *k*, of sufficient size to receive the collars *c* *c'*. The outer portions of said guide are made in sections 6, which are connected to the inner portions by 100 screws or bolts 7 7, passing through lugs 8 8, formed on the respective parts, as shown in

Figs. 2 and 3. The lugs and bolts at one side may serve as hinges, so that the sections may be swung outwardly to permit the insertion of the rope *b* into the guides, the bolts at the 5 other end being removed to permit the displacement of the sections.

Each collar is split lengthwise at one side, so that it may be sprung upon the rope *b*, and is secured to the rope by a split clamping-ring 9, the ends of which are connected by a screw 10. The ring 9 is placed upon a reduced portion of the collar, and is contracted by the screw 10 to bind the collar upon the rope. 10

15 I claim—

1. An elevator-lock composed of a holder or casing, a pair of spring-closed separable jaws pivoted thereto, and a movable key or lever interposed between said jaws, the latter being recessed at their inner sides to receive the key or lever when the same is moved to one position and provided with cheeks or surfaces 2 2, arranged to be displaced by the key or lever when it is moved to another position, 20 as set forth. 25

2. The combination of the holder or casing provided with means for attachment to an elevator and provided with a rope guide or guides, the spring-closed jaws pivoted to said holder and having their free ends arranged to engage a collar on the shipping-rope, and the pivoted lever interposed between the jaws, the latter having cheeks or surfaces 2 2, arranged to be displaced by a movement of the lever, as set forth. 30

3. The jaw holder or casing having the rope-guides *k* *k*, composed of two sections, one of which is formed on the casing and the other detachably connected and adapted to be displaced, as set forth. 35

In testimony whereof I have signed my name to this specification, in the presence of two subscribing witnesses, this 10th day of January, A. D. 1889. 40

EDWIN E. ANGELL.
